UNITED STATES PATENT OFFICE.

ARTHUR E. COLGATE, OF NEW YORK, N. Y.

THERMOSTATIC APPARATUS.

1,412,773.

Specification of Letters Patent. Patented Apr. 11, 1922.

Application filed May 18, 1920. Serial No. 382,370.

To all whom it may concern:

Be it known that I, ARTHUR E. COLGATE, a citizen of the United States of America, residing at city of New York, county and 5 State of New York, have invented a new and useful Thermostatic Apparatus, of which the following is a specification.

My invention relates to an apparatus for automatically shutting off and turning on 10 gas, the same being responsive to temperature changes. My invention, as particularly shown herein, may be used to great advantage in connection with hot water boilers such as installed in kitchens and in which 15 the water is heated by an auxiliary gas heater attached thereto. In said boilers if the temperature is too high, the water will be blown out of the boiler and explosion is liable to result. By applying my invention 20 to the side of such a boiler and properly setting the same, when the temperature reaches a predetermined point it will operate to turn off the main gas supply of the gas heater, so as to leave only the pilot light 25 going. When the temperature within the boiler descends below that point, the gas of the main burner will be automatically turned on again, and so on.

The object of the invention is to provide 30 an exceedingly simple, efficient and comparatively inexpensive apparatus for accomplishing the above purposes.

In the drawings I have shown in more or less conventional fashion one preferred 35 form of my invention, in which—

Fig. 1 is a section of the casing or housing showing certain internal parts in front elevation;

Fig. 2 is a section of the same housing at 40 right angles to the section of Fig. 1, and showing certain internal parts in side elevation;

Fig. 3 is a view of certain details;

Fig. 4 is a diagrammatic view showing 45 the parts in a different position from that shown in Fig. 1; and

Fig. 5 is a detail.

1 represents a gas tight housing or casing having a gas inlet 2 to which a gas supply 50 pipe may be attached and having a gas outlet 3 to which a gas outlet pipe may be attached. In practice the gas leading to the burner to be controlled flows through the housing aforesaid. 4 is a valve for cutting off the passage of gas through the said 55 housing. 5 represents a lever, pivoted at 6

upon a suitable support 7. The valve 4 in the particular form shown is mounted upon a stem 4^a which has suitable end guides. 5^a is an extension on the free end of the lever 60 5, which has a passage through which the valve stem 4^a freely passes. Mounted upon the valve stem 4^a, on opposite sides of the extension 5^a, are two spaced abutments 8, 8^a. 9, 10 are magnets which face each other, as 65 best seen in Fig. 3, but which are somewhat spaced apart. The end of the extension 5^a stands between the ends of said magnets and constitutes an armature. 11 is a spring carried by the arm 5. 12 is an abutment 71 against which the end of the spring bears. This abutment is movable for adjusting the effective tension of the spring. In the form shown, the abutment is mounted upon a stem 13, which has a threaded, gas-tight fit 71 in the wall of the housing, but so that access may be had to the outer end of the screw to turn it to vary the spring tension as desired.

14 is a lever pivoted at 15 within the housing, the free end of this lever being arranged to engage the lever 5 intermediate its length at certain times and for a certain purpose, as hereinafter described. 16 is a thermostat, which bears against the back wall of the 80 housing 1, so as to be responsive to the temperature thereof. In the particular form shown, this thermostat 16 is constructed to expand and contract after the manner of an accordion or bellows, the same being preferably filled with a gas or liquid sensitive to 85 temperature changes, for example, ether. 17 is a center bearing carried by the front wall of the thermostat and passing freely through a hole in a supporting bar 18, so 90 that the nose of said center bearing may engage the back of the lever 14. 18' is a light spring for holding the thermostat with its back against the back of the housing.

It will be seen that in the preferred form 100 herein disclosed the bellows thermostat 16 is loosely or non-rigidly mounted in the casing, that is, the bellows is not secured to the casing but rests flatwise against and is simply supported between the back of the 105 casing or housing and the supporting bar 18. The pin 17 on the thermostatic element passing through the aperture in the bar 18 serves to position the bellows in a lateral direction.

110 Various adjustments may be provided, for example, the magnets may be adjusted

to and fro, being held by suitable clamping means, as shown. The free end of the lever 14 may likewise be adjusted, being held by suitable screws 14^a.

5 In operation, it is obvious that the lever 5 will be yieldingly held in either one of two positions by the magnets 9, 10; that is to say, when the armature end thereof is adjacent to the magnet 9, it will be held in 10 the position shown in Fig. 2, and when the armature end is adjacent to the magnet 10, it will be held in the position indicated in 15 Fig. 4. In Fig. 2 the valve 4 is open, whereby the gas may freely flow through the housing of the main burner; whereas, in Fig. 4, it is obvious that the parts are in a position to cause the valve 4 to close. The spring 11 should be adjusted so that it will tend to move the lever 5 in a direction to 20 cause the armature end to move toward the magnet 9.

Now, assuming the temperature of the back of the housing is increased to a sufficient extent to expand the thermostat 16, 25 the action will be as follows:

As the thermostat expands and the power thereof increases, the end of the lever 14 will engage the lever 5 but will not move it until the power applied is sufficient to overcome the power of the magnet 9 plus the 30 power of the spring 11. When, however, the power of the thermostat becomes sufficiently great, and the parts should be adjusted so that this will occur when the temperature reaches a predetermined point, then the 35 armature will break away from the magnet 9, and the extension 5^a will strike against the abutment 8 with a snap action, closing the valve 4 and shutting off the gas to the 40 main burner and incidentally bringing the armature into contact with the magnet 10. The flame being now cut off, the temperature lowers and the thermostat 16 weakens. When the said thermostat has weakened sufficiently 45 the spring 11 will exert sufficient power to pull the armature away from the magnet 10 and cause it to snap back from the position shown in Fig. 4 to the position shown in Fig. 2. This movement causes the 50 armature extension 5^a to strike against the abutment 8^a and open the valve 4. On this movement the center of the thermostat diaphragm may slightly buckle under the influence of the spring 11, but that, obviously, 55 may occur as the said thermostat is in a weakened condition owing to the lowered

temperature. This buckling, of course, is only sufficient to allow the aforesaid snap action to take place.

The lever 14, lever 5, and stem 4^a constitute a lost motion connection between the valve 4 and the thermostatic element 16. As will be obvious from an inspection of Fig. 2, the thermostat will move an appreciable distance before the lever 14 will be caused 65 to move the lever 5 and consequently the valve stem 4^a and valve 4.

It will be seen that the effect of each of the magnets 9 and 10 is to exert a sufficient drag on the armature so that movement of 70 the lever 5 will not occur until there has been a sufficient storage of power to effect the aforesaid snap action, which is desirable, and, indeed, necessary in many cases to guarantee the effective extinguishing of 75 a gas burner, particularly of the Bunsen type.

I claim:

1. A thermostatic valve operating mechanism comprising, a casing having a gas inlet and a gas outlet, and having a wall adapted to be applied directly to the wall of a water heater, an expandible bellows thermostatic element within the casing with the rear wall thereof resting flatwise against 85 the first mentioned wall of the casing whereby heat from said water heater will be transmitted directly to said thermostatic element through said walls, a valve in said casing for said gas outlet, a lost motion connection 90 between said valve and said thermostatic element including means for multiplying the degree of movement of the latter relatively to the degree of movement of the thermostatic element, and magnetic means for 95 opposing the starting movement of said valve from its open position toward its closed position, and vice versa.

2. A thermostatic valve operating mechanism including a casing having a wall 100 adapted to be applied directly to the wall of a water heater, a gas passage through said casing and a valve therefor, a bellows thermostatic element non-rigidly mounted in said casing, a lost motion connection between said bellows and said valve, a spring 105 for urging one wall of the bellows at all times into contact with one wall of said casing, and means of connection between said element and said valve.

ARTHUR E. COLGATE.
